UNITED STATES PATENT OFFICE.

MYER METZGER, OF CHICAGO, ILLINOIS.

HOLDER FOR MENU-CARDS AND THE LIKE.

1,310,202.

Specification of Letters Patent. Patented July 15, 1919.

Application filed March 25, 1918. Serial No. 224,405.

To all whom it may concern:

Be it known that I, MYER METZGER, a citizen of the United States, residing at Chicago, in the county of Cook and State of Illinois, have invented certain new and useful Improvements in Holders for Menu-Cards and the like, of which the following is a specification.

This invention relates to improvements in 10 holders particularly adapted, though not necessarily limited in its use for holding menu cards.

Heretofore holders of this character have been provided with spring members between 15 which the menu card has been placed, and considerable difficulty has been experienced in that the patrons have weakened the spring by drawing the finger or hand between the spring members when the card is removed, 20 with the result that the card will not be retained in the holder and will fall over or out of the holder.

To overcome these difficulties and objections and to provide improved means which 25 will cause the spring members to retain their elasticity and which means will prevent injury to the members by the insertion of the hand or finger between the members, is one of the objects of the present invention.

30 To the attainment of these ends and the accomplishment of other new and useful objects as will appear, the invention consists in the features of novelty in substantially the construction, combination and arrangement of the several parts as hereinafter more fully described and claimed and as shown in the accompanying drawings; and in which—

Figure 1, is a view in front elevation and 40 partly in section of an improved device of this character constructed in accordance with the principles of this invention.

Fig. 2, is a detail horizontal view as taken on line 2—2, Fig. 1.

45 Fig. 3, is a vertical sectional view as taken on line 3—3, Fig. 1.

Fig. 4, is a view similar to Fig. 1, of a modified form of the invention.

Fig. 5, is a horizontal sectional view as 50 taken on line 5—5, Fig. 4.

Fig. 6, is a vertical sectional view as taken on line 6—6, Fig. 4.

Fig. 7, is a view similar to Fig. 1, of still 55 another modified form of the invention.

Fig. 8, is a vertical sectional view as taken on line 8—8, Fig. 7.

Referring more particularly to the drawing, the numeral 10, designates a support of any desired size and constructed of any suitable material, preferably sheet material 60 shaped to form a tray of any suitable configuration.

The holder proper is preferably formed from a single piece of sheet material shaped to form two opposed and coöperating members 11, 12, with a connecting base 13, therebetween, and the members are constructed of elastic material so that the tendency of the members will be to spring toward each other so as to hold a card yieldingly there- 65 between. Obviously the members may be of any desired contour and are of a length that when secured to the support 10, they will project for a considerable distance thereabove. 70

The members 11, 12 are preferably shaped to form extended areas for the reception of advertising matter and may be secured to the support 10, in any suitable manner such as by means of ears or lugs 14, formed integral with the connecting base 13, and which are adapted to pass through suitable apertures in the support 10, preferably through a raised portion 15, of the support, to the opposite side of the support and then 85 flanged over against the face of the support as clearly seen in Fig. 1.

In order to protect the members 11, 12, so that they will not lose their elasticity and become useless for holding the card inserted 90 therebetween, by the insertion of the hand or fingers of the patrons while "playing" with the holder, suitable reinforcing means such as ears or projections 16 may be formed on the member 11, adjacent the base 13, but 95 spaced above the support 10, to project in a direction across the space between the members with their extremities flanged or bent over the opposite face of the other member 12, to limit the separating movement of the 100 members.

Obviously these ears or projections are of a size and shape as not to interfere with the operation of the device nor the insertion of a card between the members or the withdrawal of the card therefrom. 105

In the form of the invention as shown in Figs. 4 to 6, the ears or projections 17, are formed by cutting out a portion of one of the members at a suitable distance above the 110 support and then passing these ears through suitable apertures or slots 18, in the oppo-

site member and flanging the extremities of the ears against the face of the other member.

In the form of the invention as shown in 5 Figs. 7 and 8, there is shown another form of strengthening or protecting device such as a rivet 19, which is adapted to be passed through both of the members 11, 12, and serves the same purpose as the other reinforcing devices:

The members 11, 12, may also be fastened to the support 10, by means of a rivet 20, if desired, and as shown in Figs. 7 and 8 the support may be inverted.

15 With this improvement it will be manifest that it will be impossible to destroy the elasticity or spring of the members 11, 12, by inserting or drawing anything between the members, and as a result a yielding gripping 20 of the card between the members will be assured.

While the preferred forms have been herein shown and described, it is to be understood that various changes may be made in 25 the details of construction without departing from the spirit of this invention.

What is claimed as new is:

1. A menu card holder embodying a supporting base, a clamp connected with and 30 projecting above the base for a considerable distance, said clamp embodying coöperating spring members between which the card is yieldingly held, each of said members having extended areas for the reception of advertising matter, and fastening means connected with the members intermediate the base and ends of the members and spaced above the base, the said fastening means being disposed within the confines of the edges 35 of the members and embodying a fastener supported by one of the members and extending through the other member with its extremity flanged against the face of the last recited member, said fasteners operating to hold the adjacent portions of the clamp 40 members in close proximity to each other and serving to reinforce the members and limit their separation, both of said members being adapted to be freely flexed toward 45 and away from each other.

2. A menu card holder embodying a supporting base, a clamp, means for securing the clamp to the base, said clamp projecting above the base for a considerable distance and embodying coöperating members 55 between which the card is yieldingly held, and means connected with the said members intermediate the base and the ends of the members and spaced above the base for reinforcing the members and for limiting the separation of the members, the last recited means embodying a projection formed integral with one of the members, said projection extending in a direction across the 60 space between the members and extending 65

through one of the members with its extremity bent to extend over a portion of the last recited member.

3. A menu card holder embodying a supporting base, a clamp, means for securing the clamp to the base, said clamp projecting above the base for a considerable distance and embodying coöperating members between which the card is yieldingly held, and means connected with the said members intermediate the base and the ends of the members and spaced above the base for reinforcing the members and for limiting the separation of the members, the last said means embodying an ear or projection 70 formed integral with one of the members and bent to extend in a direction across the space between the members, the extremity of the projection being flanged or bent over 75 a portion of the other member.

4. A menu card holder embodying a supporting base, a clamp, said clamp being formed from a single piece of sheet material and shaped to form coöperating spring members having a connecting base therebetween and between which members the card is yieldingly held, said base resting upon the support with the said members projecting thereabove, means for securing the base and support together, and means spaced 90 above the base and support and coöperating with the said members for limiting their separating movement, the last recited means embodying an ear formed integral with one of the members, the extremity of said ear 95 being flanged over a portion of the other member.

5. A menu card holder embodying a supporting base, a clamp, said clamp being formed from a single piece of sheet material and shaped to form coöperating spring members having a connecting base therebetween and between which members the card is yieldingly held, said base resting upon the support with the said members projecting thereabove, means for securing the base and support together, and means spaced 105 above the base and support and coöperating with the said members for limiting their separating movement, the last recited means embodying an ear or projection 110 formed integral with one of the said members and deflected to extend in a direction across the space between the members, the extremity of said projection being bent to 115 overlap the other member.

6. A menu card holder embodying a clamp formed from a single blank of sheet material and bent into shape to form coöperating clamping members with a connecting base between the members, an ear also on one of the members and formed integral therewith, said ear being spaced above the said connecting base and deflected to extend 125 across the space between the members, the 130

5 said members having wide or extended surfaces to form a space for the reception of advertising matter, the extremity of the ear being bent or flanged over a portion of the other member for limiting the separating movement of the members, a support, and means for securing the support and the said connecting base together.

10 7. A menu card holder embodying a supporting base, a clamp connected with and projecting above the base for a considerable distance, said clamp embodying coöperating members between which the card is yieldingly held, and fastening means for the 15 members, intermediate the base and ends of

the members and spaced above the base, the said fastening means being disposed within the confines of the edges of said members, said fastening means operating to hold the adjacent portions of the clamp 20 members in close proximity to each other and serving to reinforce the members and limit their separation, both of said members being adapted to be freely flexed toward and away from each other.

25 In testimony whereof I have signed my name to this specification, on this 19th day of March, A. D. 1918.

MYER METZGER.
